VALVE ADJUSTMENT APPARATUS

Thomas J. Hoy, Newark, N. J.

Application January 8, 1945, Serial No. 571,745

15 Claims. (Cl. 121—162)

1

This invention relates to valves and valve gears and more particularly to valves and valve gears for steam locomotives, reciprocating steam engines and the like.

The present invention provides a valve gear and a power reverse gear by means of which the admission valve and the exhaust valve of a steam engine having separate admission and exhaust valves are actuated independently of one another and are variably controlled in relationship to each other at a predetermined rate so that the rate of flow of steam to and the rate of flow of steam from the power cylinder or cylinders is variably controlled in relationship to each other at a predetermined rate.

This invention also provides a piston valve in which the sliding friction is greatly reduced by preventing leakage past the rings and thereby improving lubrication.

The invention will be understood from the following description when considered in connection with the accompanying drawings forming a part thereof and in which:

Fig. 1 is a longitudinal sectional view of the mechanism for actuating the valve gear of the present invention in its single action embodiment;

Fig. 2 is a transverse sectional view taken on the line 2—2 of Fig. 1;

Fig. 3 is a side elevational view of the cab of a locomotive and the controls therein by means of which the mechanism for actuating the valve gear of the present invention is operated;

Fig. 4 is a sectional view of a gauge for giving visual indication of the adjustments made of the mechanism for actuating the valve gear of the present invention;

Fig. 5 is a view similar to Fig. 1 but of a multiple-action embodiment of the mechanism for actuating the valve gear of the present invention;

Fig. 6 is a fragmentary perspective view of the compound link, tumbling shafts, eccentric rod and radius rods used in the preferred embodiment of the present invention, said mechanism being shown in the full forward or 90% cut-off position;

Fig. 7 is a longitudinal sectional view of a cylinder and exhaust valve of a steam locomotive taken on the line 7—7 of Fig. 9;

Fig. 8 is a longitudinal sectional view of a cyl-

inder and admission valve of a steam locomotive taken on the line 8—8 of Fig. 9;

Fig. 9 is a front view of the cylinder, admission and exhaust valve on the right hand side of a locomotive;

Fig. 10 is a graph of the valve movement of the admission and exhaust valves at a 5 to 1 ratio;

Fig. 11 is a longitudinal sectional view of an admission piston valve embodying the present invention;

Fig. 12 is a view similar to Fig. 11 but of an exhaust piston valve, and

Fig. 13 is a perspective view of the piston ring and holding means of the valves shown in Figs. 11 and 12.

Like characters of reference refer to like parts throughout the several views.

Referring to Fig. 1, the valve gear actuating mechanism in its single action embodiment is somewhat similar to that disclosed in my United States Patent No. 2,243,865 issued June 3, 1941 and comprises a housing 10 having a screw-threaded shaft 11 journaled adjacent opposite ends thereof in journals 12 and 13 which, as shown, are integral with the housing 10. A thrust bearing 14, for taking care of axial thrusts of the shaft 11 is mounted in the journal 12. The shaft 11 has a flanged member 15 secured thereto and connected to a cardan-shaft 16 so that rotation of the cardan-shaft 16 will rotate the shaft 11 through the flanged member 15. As shown more particularly in Fig. 3, the cardan-shaft 16 is rotated by an air motor 17 of the reversible type the operation of

which motor is controlled by a two-way valve 18 connected through pipes 19 and 20 to the motor 17. Through operation of the control valve 18 the direction in which the shaft 16 is rotated by the motor 17 is controlled, as will hereinafter be fully described.

40 A cam 21 is adapted to be moved longitudinally of the housing 10 through rotation of the shaft 11 by the cardan-shaft 16. As shown in Figs. 1 and 2, cam 21 comprises a cam nut 22 having screw-threads thereon adapted to engage the threads on the shaft 11. The nut 22 has guide members 23 at opposite sides thereof (Fig. 2) which guide members slidably engage, in dovetail relationship, a guide plate 24 secured by bolts 25 to the bottom portion of the housing 10. The

cam nut 22 has formed on the upper part thereof a cam block 26 which, in the form of the invention shown in Fig. 1, is in the shape of a right-angle triangle having a substantially vertically extending leg 27, a substantially horizontally extending leg 28 and a cam profile 29 which is the hypotenuse of the triangle. The cam profile, therefore, is in the form of an inclined plane. A pivot pin 30 is disposed in the housing 10 to extend transversely thereof and has rotatably mounted thereon a three-armed crank 31. The crank 31 has an arm 32 which extends in a general longitudinal direction in the housing 10 and a crank arm 34 which extends in a general downwardly direction and outwardly of the housing. The arm 32 has a cam roller 35 rotatably disposed thereon, the periphery of which roller is held in contact with the cam profile 29 by means of the lever 33 which is connected to a piston 36 by means of a link 37 which is pivotally connected to the piston and the lever. The piston 36 is slidably positioned in a cylinder 38 formed in the housing 10. Fluid pressure enters the cylinder 38 through the line 39, the pressure entering the cylinder being controlled by valve 40 in the cab of the locomotive (Fig. 3). Fluid pressure in the cylinder 38 will maintain the roller 35 in contact with the cam profile eliminating lost motion due to wear, the pressure in the cylinder determining the extent of the engaging pressure between the roller and the cam profile. A drain outlet 41 is provided for the cylinder 38 which outlet is controlled by a drain cock, not shown. The crank arm 34 of the three-arm crank 31 has a pivot pin 42 upon which an actuating rod 43 is pivotally mounted at one end thereof. The opposite end of the actuating rod is connected to valve positioning gear, for example a reversing shaft connected to valve gears, not shown. By means of the valve positioning gear the position of a piston valve is controlled, for example, from between a position in which the locomotive is running in a full forward direction to a position in which the locomotive is running in a full reverse direction.

In Fig. 4 is shown a gauge 44 by means of which visual indication is given in the cab of a locomotive of the adjustments made to the valve gear. This gauge is fully described in my United States Letters Patent No. 2,243,865 issued June 3, 1941 and comprises a shaft 45 which is actuated by the reversible motor 47. The shaft 45 has a pinion gear 46 secured thereto to rotate therewith which gear is rotatably mounted in a housing 47 and is enmeshed with another pinion gear 48 secured to a screw-threaded shaft 49 which has an indicator block 50 thereon and movable thereby. The indicator block has a pointer 51 thereon which moves over a scale 52. The shaft 45 has a hand wheel 53 thereon. Rotation of the shaft 45 in one direction by the reversible motor 47 causes movement through the gears 46, 48 and rotation of the shaft 49 of the indicator block vertically in one direction while movement of the shaft 45 in the opposite direction will cause the indicator block 50 to move in the opposite direction. In the event of failure of the motor 47, the cardan-shaft 16 can be hand operated through rotation of the hand-wheel 53.

In operation of the form of the invention shown in Figs. 1 to 4, the piston valve position is changed by actuating the two-way control valve 18 in the locomotive cab. The valve is actuated in one direction to move the actuating rod 43 in one direction and is actuated in an

opposite direction to move the actuating rod in the opposite direction. For example, when the valve handle 18' is moved forwardly, compressed air is admitted through pipe 20 to the air motor 5 17 causing the cardan-shaft to rotate in a clockwise direction which in turn rotates the shaft 11 in clockwise direction thereby moving the cam nut 22 and cam block 26 of the cam 21 forward (to the right of Fig. 1). Movement 10 of the cam block forward causes the roller 35 to rise on the inclined surface of the cam profile 29 causing the arm 32 of the crank to move in a clockwise direction. The cam roller 35, therefore, moves upwardly in an arc of which the pivot pin 30 is the center. Movement of the arm 32 in a clockwise direction causes the lever 33 and the crank arm 34 likewise to move in an arc in a clockwise direction on the pivot pin 30. Movement of the lever 33 in a clockwise direction causes the piston 36 to move to the right of Fig. 1 in the cylinder 38 while movement of the crank arm 34 in a clockwise direction causes the pivot pin 42 on which the actuating rod 43 is pivotally mounted to move in a clockwise direction in an arc of which the pivot pin 30 is the center causing the actuating rod 43 to be moved to the left of Fig. 1 thereby moving the valve positioning mechanism in one direction. The extreme position to which the roller 35 will be raised on the inclined surface or cam profile 29 is indicated in Fig. 1 by the dot and dash circle 55. When the handle 18' of the valve 18 is moved backwardly toward the rear of the cab, compressed air is admitted to the pipe 19 causing the air motor to be reversed. This causes the cardan-shaft and the shaft 11 to rotate in a counter-clockwise direction moving the cam screw 22 and block 26 backwardly (to the left of Fig. 1). As the cam block 26 moves backwardly, the cam roller moves downwardly on the inclined surface of the cam profile 29 causing the crank 31 to move in a counter-clockwise direction and the actuating rod 43 to be moved to the right of Fig. 1 by the crank arm 34. The extreme downward movement of the cam roller 35 is indicated in Fig. 1 by the dot and dash circle 56. When the actuating rod 43 has been moved to the desired extent in either 25 a forward or backward direction to thereby position the piston valve, movement of the cam block 26 is stopped by moving the valve handle 18 of the valve 18 to its neutral position thereby stopping the motor 17 and rotation of the cardan-shaft 16 and shaft 11.

The form of the invention illustrated in Figs. 5 to 10 is adapted to control the movement of the admission valve and the exhaust valve of a locomotive in relationship to each other by means of the same control so as to maintain a relationship of movement of the valves at any setting which results in the most economic utilization of steam. The actuating mechanism, as shown more particularly in Fig. 5, is somewhat similar to that shown in Fig. 1 but is adapted to actuate two actuating rods similar to the rod 43 instead of one actuating rod as shown in Fig. 1. Referring to Fig. 5, the cam nut 22 of the cam 21 has a cam block 56 having a substantially horizontally extending leg 57. The cam block 56 has two cam profiles 59 and 60, the cam profile 59 being adapted to actuate the admission valve 61 (Fig. 8) while the cam profile 60 is adapted to actuate the exhaust

valve 62 (Fig. 7) as will hereinafter be fully set forth. The cam profile 59 has an intermediate flat or horizontally extending portion 63 extending between two inclined portions 64 and 65, (Figs. 5 and 10), the portion 64 extending between the forward end of the flat portion 63 and the forward end of the leg 57 while the inclined portion 65 extends between the rearward end of the flat portion 63 and the upper end of the leg 58. The profile 60 has an inclined portion 66 which is relatively steeply inclined composed with portions 64 and 65, extending between flat or slightly inclined portions 67 and 68 (Figs. 5 and 10). The portion 67 extends from the forward end of the leg 57 to a point in substantially the same vertical plane as the forward end of the flat portion 63 of the profile 59, from which point the inclined portion 66 extends to another point which other point is in substantially the same vertical plane as the rearward end of the flat portion 63. The inclined portion 68 of the profile 60 extends from said other point to the upper end of the leg 58. The legs 64 and 67 of the profiles 59 and 60 respectively are substantially the same length and the portions 65 and 68 of the profiles 59 and 60 respectively are substantially the same length. The horizontal distance between points where opposite ends of the inclined portion 66 of the profile 60 connect respectively with the portions 67 and 68 and the length of the horizontal portion 63 of the profile 59 is substantially the same (Fig. 10). As in the form of the invention shown in Fig. 1, the roller 35 is held in engagement with the cam profile by means of fluid pressure, the cam roller 35, as shown in Fig. 5, being held in engagement with the cam profile 59 by pressure in the cylinder 38 acting on the piston 36 to cause the link 37 to exert a counter-clockwise pressure on the crank 31. In the form of the invention shown in Fig. 5, a second crank, crank 70, is pivotally mounted on the pivot pin 30. The crank 70 is similar to the crank 31 having an arm 71 which extends in a general longitudinal direction in the housing 10, a lever 72 which extends in a general upwardly direction and a crank arm 73 which extends downwardly and outwardly of the housing through the bottom plate 10' thereof. The arm 71 has a cam roller 74 rotatably disposed thereon which roller engages the cam profile 60 of the cam block 56. The roller 74 is held in engagement with the profile 60 by the lever 72 connected to a piston 75 by means of a link 76 which is pivotally connected to the piston and the lever 72. The piston 75 is slidably positioned in a cylinder 77 in the housing 10 beneath the cylinder 38. Fluid pressure enters the cylinder 38, as in the form of the invention shown in Fig. 1, through the pipe 39 which pressure enters the cylinder 77 through a passage 78. The pressure in the cylinders 38 and 77 is, therefore, the same and the roller 74, like the roller 35, is held in engagement with the cam profile with which it is associated. The crank arm 73 of the crank 70 has an actuating rod 79 pivotally connected thereto at 80.

The actuating rods 43 and 79 are pivotally connected respectively to arms 81 and 82 by pins 83 and 84, while the arms 81 and 82 are secured respectively to shafts 85 and 85' and are respectively connected to arcuate-shaped levers 86 and 87. The shafts 85 and 85' extend between

opposite sides of the locomotive, the shaft 85 being rotatably mounted inside the shaft 85' while the shaft 85' is rotatably mounted in respect to the locomotive frame. A hanger 88 is pivotally connected at one end thereof to the lever 86 and at the opposite end is pivotally positioned in a clevis of a radius rod 89 which in turn is connected to the admission valve through the lap and lead lever 90. Through the union link 92 the cross-head (not shown) actuates the lap and lead lever 90 providing lap and lead movement for the admission valve 61. The clevis end of the radius rod 89 is pivotally secured to a block 93 which is slideable in a guideway 94 in a compound link 95. The compound link comprises side member 95' and 95'' spaced from one another by a spacer 98. The guideway 94 is in the member 95' and the member 95'' has a similar guideway. The arcuate lever 87 is pivotally connected to a radius rod 96 through a hanger 97 which hanger is pivoted at one end on the arm 87 and at the other end in a clevis at one end of the radius rod 96. The rod 96 is pivotally connected directly to the valve rod 97 of the exhaust valve 62. The clevis end of the radius rod 96 is pivotally connected to a slide block (not shown) similar to the block 93 which slides in the guideway in the member 95''. The compound link 95 is bolted to the eccentric rod 99 which eccentric rod is adapted to be actuated by the drive wheel of a locomotive in the usual manner. A mounting arm 100 is secured to the members 95' and 95'' intermediate the opposite ends thereof and extends outwardly and away from said members a sufficient distance to permit free movement of the clevis of the radius rod 89 and the block 93 in the guideway 94 from one end to the other of said guideway. A pivot pin 101 is secured to the arm 100 and is adapted to be mounted in any desired manner on the locomotive frame so that the compound link will rock thereon when actuated by the eccentric rod 99. Levers 86 and 87, hangers 88 and 97, radius rods 89 and 96, compound link 95, and cylinder 103 with valves 61 and 62 are duplicated on the left hand side of the locomotive.

Referring to Figs. 7 to 9, the admission valve 61 is slidable in a valve chamber 102 which chamber communicates with the cylinder 103 through a forward port 104 and a rear port 105. A piston 106 is reciprocally disposed in the cylinder 103 and actuates a piston rod 107, which through well-known mechanism not shown, is connected to the drive wheels of the locomotive. The valve chamber 102 receives steam through the intake conduit 108. The exhaust valve 62 is slidable in a valve chamber 109 which chamber is in communication with the cylinder 103 through a forward port 110 and a rearward port 111. Steam from the chamber 109 is exhausted through the exhaust conduit 112. As shown in Figs. 7 and 8, the admission valve 61 is inside admission and the ends of the valve overlap the ports 104 and 105 to prevent exhaust of steam from the cylinder 103 while the exhaust valve 62 is adapted to release past the ends thereof through the ports 110 and 111. The body portion of said exhaust valve overlaps the ports to prevent admission of cylinder pressure to the body portion of the exhaust valve.

The admission and exhaust valves may be of the type shown in Figs. 7 and 8 or may be of the type shown in Figs. 11 and 12 in which an admission valve is disclosed in Fig. 11 and an exhaust valve is shown in Fig. 12. The admission valve 113 and the exhaust valve 114 are slidably positioned respectively in valve chambers 115

and 116 which, as shown, comprise a cylindrically shaped sleeve secured in housings 117 and 118 respectively. The sleeve 115 has admission ports 119 and 120 therein through which steam is admitted to the sleeve 115 while sleeve 116 has exhaust ports 121 and 122 therein through which steam is exhausted from sleeve 116. The exhaust valves 113 and 114 comprise a tubular body portion 123 having a spider 124 therein. The body portion is flanged along one edge at 125 while at the other edge the body portion is secured to a member 126 having a flange 127. The flanges 125 and 127 form a groove in which a spacer 128 is positioned intermediate the flanges and spaced therefrom to form two spaces in which piston rings 129 and 130 are disposed. The piston rings 129 and 130 comprise an inner ring 131 and an outer ring 132 of larger diameter than the inner ring and spaced therefrom. The rings 131 and 132 consist of two substantially semi-circular sections which sections are spaced from one another. The rings 131 and 132 are secured respectively to the inner periphery and the outer periphery of a bellows-like, preloaded diaphragm 133. The diaphragm 133 comprises a plurality of annular leaves 134 of flexible material superimposed in spaced relationship to one another, each leaf being connected adjacent opposite edges thereof to the leaf adjacent opposite sides thereof thereby to form a plurality of flexible hinges. Since the diaphragm 133 is preloaded, it acts to hold the ring 129 in tight engagement with the body 123. The inner ring 131 has an annular groove in the inner periphery which engages an annular projection 135 so as to position the piston ring in respect to the piston. With the rings 129 and 130, any wear on the outer ring 132 and the inner periphery of the valve chamber is compensated for by the diaphragm 133 which holds the ring 132 in fluidtight engagement with the inner periphery of the valve chamber at all times, thusly preventing leaks.

In operation of the form of the invention disclosed in Figs. 5 to 10, the position of the cam nut 22 and cam block 56 is changed to change the position of the piston valves by operation of the cardan-shaft 16 from the cab of the locomotive which actuates the screw-threaded shaft 11 in substantially the same manner as in the operation of the form of the invention shown in Figs. 1 to 4 as hereinbefore described. As the cam block 56 moves forward (to the right in Fig. 5), the cam roller 35 rises on the inclined leg 64 of the cam profile 59 causing the crank 31 and the crank arm 34 thereon to move in a clockwise direction. Movement of the crank arm 34 in a clockwise direction moves the actuating rod 43 to the left of Fig. 5 which in turn rotates the arm 82, rod 85' and lever 86 in a counterclockwise direction. Rotation of the arm 82, rod 85' and lever 86 in a counterclockwise direction moves the hanger 88 in an upwardly direction which raises the radius rod 89 at the clevis end thereof, the block 93, to which the clevis end of the radius rod is pivoted, sliding upwardly in the guideway 94 in the compound link 95 thereby shortening the distance of travel of the radius rod 89 and the admission valve 61 which is actuated thereby. As is usual in the operation of locomotive, the compound link 95 is reciprocated by the eccentric rod 99, the link, in turn, imparting a reciprocal movement to the radius rods 89 and 96. Forward movement of the cam block 56 likewise causes the cam roller 74 on the crank 70 to move along the cam profile 60 rising on the leg 67, but only slight-

ly in comparison with the rise of the roller 35 on the leg 64 of the profile 59. Upward movement of the roller 74 causes the crank 70 to rotate in a clockwise direction and thereby move the actuating rod 79 to the left of Fig. 5 thereby rotating the arm 81 and lever 87 in a counterclockwise direction. Rotation of the arm 81 and lever 87 in a counterclockwise direction moves the hanger 97 and the clevis end of the radius rod 96 upwardly, the block to which the clevis end of the rod 96 is pivoted sliding upwardly in the guideway of the link 95', thereby shortening the length of travel of the radius rod 96 and the exhaust valve 62 which the radius rod 96 actuates. When the cam 56 is so positioned that the cam roller passes from the inclined leg 64 of the profile 59 onto the flat portion 63 thereof, the cam roller 74 of the crank 70 rises abruptly on the inclined portion 66 of the cam profile 60 thereby abruptly shortening the travel of the exhaust valve through shortening the distances the radius rod 96 travels. This occurs when the movement of the locomotive is being changed from a forward movement to a reverse movement thereby requiring a change of movement of the admission and exhaust valves. Upon further forward movement of the cam block 56, the roller 35 passes from the flat portion 63 of the cam profile 59 while the roller 74 passes from the vertically inclined portion 66 of the profile 60 onto the portion 68 thereof. When the roller 35 is at the center of the flat portion 63 of the profile 59 and the roller 74 is at the center of the vertically inclined portion 66 of the profile 60, (position x of Fig. 10) the rollers are in horizontal alignment as are the clevis ends of the radius rods 89 and 96, the clevis ends of said radius rods also being in horizontal alignment with the pivot pin 101 of the combination lever 95. Movement of the cam block forward (to the right in Fig. 5) from this point places the admission and exhaust valves at the beginning of their reversing movement cycle while movement of the cam block backward (to the left in Fig. 5) returns the valves to their forward movement cycle.

The relative travel of the radius rods 89 and 96 may be clearly understood by referring to Fig. 10 in which the radius rod travel of the rod actuating the admission and cut off valve and the radius rod travel of the rod actuating the release and closure valve (exhaust valve) is graphically illustrated. The dimensions given in Fig. 10 of the drawing are given merely by way of example and are not to be construed as having a limiting effect. It will be noted that as the cam block 54, by operation of the valve 18 in the locomotive cab, is moved, the travel of the admission valve and the exhaust valve is simultaneously adjusted, the distance of travel of the valves in relationship to each other at a given setting of the cam block being predetermined. Therefore, it is merely necessary for the operator to move the handle 18' of the valve 18 so as to operate the motor 17 until the gauge 44 indicates that the desired position of the cam block 56 has been reached. When the desired position is reached, the valve 18 is set in its neutral position and the motor 17 ceases operation. The ratio of travel of the admission and exhaust valves at any given position is automatically set to make the most economical utilization of the steam and is free from misjudgment on the part of the operator as the operator does not determine the relative travel of the valves. By way of example, eight settings of cam block 54 are

shown by indicating eight different relative positions of the rollers 35 and 74 on the cam profiles 59 and 60 respectively. The relative travel of the radius rod 89 and admission valve 61 and of the radius rod 96 and release or exhaust valve 62 at the various positions indicated is as follows:

	Position	Admission and Cut-Off (Valve 61)	Release and Closure (Valve 62)	Relative Travel Difference
A	Cut-off 90%	Valve travel 8.00"	Valve travel 8.00"	0"
B	Cut-off 67 1/2%	Valve travel 6.00"	Valve travel 7.60"	1.60"
C	Cut-off 45%	Valve travel 4.00"	Valve travel 7.20"	3.20"
D	Cut-off 22 1/2%	Valve Lead travel 2.00"	Valve travel 6.80"	4.80"
E	Cut-off 11 1/4%	Valve Lead travel 1.00"	Valve travel 6.60"	5.60"
F	Cut-off 5 5/8%	Valve Lead travel .50"	Valve travel 6.50"	6.00"
G	Cut-off 0%	Valve Lead travel .00"	Valve travel 6.40"	6.40"

With the locomotive running in forward motion, the cam block is moved so as to position the rollers 35 and 74 at the position indicated at A which is the 90% position shown in Fig. 10 and corresponds to the position of the radius rods in the link as shown in Fig. 6. In this position, the travel of both the the exhaust and admission valves is 8". In this position, which is the position used for starting heavy trains, the admission valve alternately admits steam during 90% of its forward and backward strokes. The exhaust valve 62, actuated by the radius rod 96, combination link and connecting levers, serves to alternately exhaust steam from the cylinders. The position indicated by A, the center position indicated by X, and full reverse position indicated by Y are the only positions in which the radius rods 89 and 96 are side by side in the link 95 and distance of travel of the radius rods 89 and 96 is same. To increase the speed of the locomotive, the cam block 54 is moved to the right of Figs. 5 and 10, the distance of travel of the radius rod 89 and the admission valve 61 being gradually decreased, as shown in Fig. 10 and in the foregoing table. The valve travel of the valve 62 controlling exhaust and closure, however, decreases at a much slower rate from the 90% position shown at A to the 0% position shown at G, after which the length of the exhaust valve travel decreases rapidly across the center position as shown at X to the early cut-off position shown at H. With the radius rods 89 and 96 on either side of the link 95 center position, which position is indicated at 101 in Fig. 6 and at X in Fig. 10, the admission valve 61 will move the amount of the lap and lead plus. The exhaust valve 62 will open the amount of the clearance plus.

Movement of the shafts 85 and 85' by actuating rods 79 and 43 through arms 81 and 82 actuates the valve gear on the left hand side of the locomotive simultaneously with and in the same manner as the valve gear on the right hand side of the locomotive as hereinabove described.

Since changes may be effected in the forms of the invention selected for disclosure without departing from the principles of the invention, it will be understood that the invention is not to be limited except by the scope of the appended claims.

What is claimed is:

1. In valve gear for steam engines, locomotives and the like having a plurality of cylinders each with an admission valve and an exhaust

valve and a reciprocating actuation rod for each valve to impart travel thereto, valve timing means comprising a cam having at least two profiles, single control means for actuating said cam, admission valve adjusting means operatively engaging one of said cam profiles and connected to the

admission valve actuating rods for simultaneously adjusting the setting of the admission valves, and exhaust valve adjusting means operatively engaging another of said cam profiles and connected to the exhaust valve actuating rods for simultaneously adjusting the setting of the exhaust valve, said cam profile being so shaped as to variably adjust the setting of the admission and exhaust valves at a predetermined ratio.

2. In valve gear for steam engines, locomotives and the like having a plurality of cylinders each with an admission valve and an exhaust valve and a reciprocating actuation rod for each valve to impart travel thereto, valve timing means comprising a cam having at least two profiles, single control means for actuating said cam, admission valve adjusting means operatively engaging one of said cam profiles and connected to the admission valve actuating rods for simultaneously adjusting the setting of the admission valves, and exhaust valve adjusting means operatively engaging another of said cam profiles and connected to the exhaust valve actuating rods for simultaneously adjusting the setting of the exhaust valves, said cam profiles being so shaped as to impart a variable adjusting movement to the admission and exhaust valves to change the setting of said valves at a predetermined ratio, said one cam profile being so shaped in relationship to said other cam profile as to impart an adjusting movement to the admission valves five times the adjusting movement imparted to the exhaust valves.

3. In steam engines, locomotives and the like having a plurality of cylinders each with a valve for admission and cut-off, and a valve for exhaust and release, a set of valve gear reversing mechanisms for the valves of each cylinder comprising a reciprocating actuation rod for each valve to impart travel thereto, valve timing means having a cam with at least two profiles, single control means for actuating said cam, admission and cut-off valve adjusting means operatively engaging one of the cam profiles and connected to the admission and cut-off valve actuating rods for simultaneously imparting an adjusting movement to the admission and cut-off valves, and exhaust and release valve adjusting means operatively engaging another of the cam profiles and connected to the exhaust and release valve actuating rods for simultaneously imparting an adjusting movement to the exhaust and release valves.

4. In valve gear for steam engines, locomotives and the like having a plurality of cylinders each with an admission valve and an exhaust valve and a reciprocating actuation rod for each valve to impart travel thereto, valve timing means comprising a cam having at least two profiles, single control means for actuating said cam, admission and cut-off valve adjusting means operatively engaging one of the cam profiles and connected to the admission and cut-off valve actuating rods for simultaneously imparting an adjusting movement to the admission and cut-off valves, and exhaust and closure valve adjusting means operatively engaging another of the cam profiles and connected to the exhaust and closure valve actuating rods for simultaneously imparting an adjusting movement to the exhaust and closure valves to change the setting of said ex-

haust and closure valves, the cam profiles being so shaped in relationship to each other that a relatively greater adjusting movement is imparted to the admission and cut-off valves than to the exhaust and closure valves during the forward and during the reverse movement of the steam engine, locomotive or the like.

4. In steam engines, locomotives and the like having a plurality of cylinders each with a valve for admission and cut-off, and a valve for exhaust and release, a set of valve gear reversing mechanisms for the valves of each cylinder comprising a reciprocating actuation rod for each valve to impart travel thereto, valve timing means having a cam with at least two profiles, single control means for actuating said cam, admission and cut-off valve adjusting means operatively engaging one of the cam profiles and connected to the admission and cut-off valve actuating rods for simultaneously imparting an adjusting movement to the admission and cut-off valves to change the setting of said admission and cut-off valves, and exhaust and closure valve adjusting means operatively engaging another of the cam profiles and connected to the exhaust and closure valve actuating rods for simultaneously imparting an adjusting movement to the exhaust and closure valves to change the setting of said exhaust and closure valves, said one cam profile having two surfaces for imparting an adjusting movement to the admission and cut-off valve adjusting means to thereby adjust the setting of the admission and cut-off valves, said surfaces being spaced from one another in the direction of travel of the cam and connected by an intermediate surface, one of the spaced surfaces adjusting the setting of the admission and cut-off valves to govern the forward movement of the steam engine, locomotive or the like and the other of said spaced surfaces adjusting the setting of said valves to govern the reverse movement of said steam engine, the intermediate surface providing an interval in which substantially no adjustment is made to the setting of the admission and cut-off valves, said other cam profile being shaped to impart a relatively lesser adjusting movement to the exhaust and closure valve adjusting means than is imparted to the admission and cut-off valve adjusting means during said forward and reverse movements and to impart a substantial adjusting movement to the exhaust and closure valve adjusting means during said interval between said portions.

5. Power reverse mechanism for steam engines, locomotives or the like in which the movements of two or more sets of valve gear reversing mechanisms are co-ordinated by means of a variable ratio transmission, said mechanism comprising a variable ratio transmission having a threaded shaft, means for rotating said shaft in clockwise and in counter-clockwise directions, single control means for controlling the rotation of said shaft, a cam nut on said shaft and actuated thereby, said cam nut having a plurality of profiles thereon, a lever connected to one set of valve gear and operable by one cam profile, and a second lever connected to another set of valve gear and operable by a second cam profile, said cam profiles being so shaped as to variably move said lever and said second lever in relationship to each other at a predetermined ratio and thereby relatively adjust the movement of said one set of valve gear and said other set of valve gear.

6. Power reverse mechanism for steam engines, locomotives or the like in which the movements of

two or more sets of valve gear reversing mechanisms are co-ordinated by means of a variable ratio transmission, said mechanism comprising a variable ratio transmission having a threaded shaft, means for rotating said shaft in clockwise and in counter-clockwise directions, a cam nut on said shaft and actuated thereby, said cam nut having a plurality of profiles thereon, a lever connected to one set of valve gear and operable by one cam profile, and a second lever connected to another set of valve gear and operable by a second cam profile, the cam profiles being so shaped as to move said lever and said second lever at substantially a five to one ratio in relationship to each other and thereby relatively adjust the movement of said one set of valve gear and said other set of valve gear at a five to one ratio.

7. Power reverse mechanism for steam engines, locomotives or the like in which the movements of two or more sets of valve gear reversing mechanisms are co-ordinated by means of a variable ratio transmission, said mechanism comprising a variable ratio transmission having a threaded shaft, means for rotating said shaft in clockwise and in counter-clockwise directions, a cam nut on said shaft and actuated thereby, said cam nut having a plurality of profiles thereon, a lever connected to one set of valve gear and operable by one cam profile, and a second lever connected to another set of valve gear and operable by a second cam profile, each cam profile having spaced surfaces connected by an intermediate surface, the spaced surfaces of said cam profiles being so shaped in relationship to each other that said one profile imparts a relatively greater movement to the one lever than the spaced surfaces of the second cam profile imparts to the second lever, the intermediate surfaces of the cam profiles being so shaped in relationship to each other that the intermediate surface of said second cam profile imparts a greater movement to the second lever than the intermediate surface of said one cam profile imparts to said one lever.

8. Power reverse mechanism for steam engines, locomotives or the like in which the movements of two or more sets of valve gear reversing mechanisms are co-ordinated by means of a variable ratio transmission, said mechanism comprising a variable ratio transmission having a threaded shaft, means for rotating said shaft in clockwise and in counter-clockwise directions, single control means for controlling the rotation of said shaft, a sliding cam nut on said shaft and moved linearly thereby, said cam nut having a plurality of profiles thereon, levers mounted to pivot on an axis extending in a plane transverse to the lineal plane in which said cam nut moves, means slidably engaging each cam profile and connected to said levers the arrangement being such that one cam profile will impart pivotal movement to one lever and the other cam profile will impart pivotal movement to a second lever, means connecting one lever to one set of valve gear, means connecting said second lever to another set of valve gear, each cam profile having spaced surfaces connected by an intermediate surface, the spaced surfaces of said cam profiles being so shaped in relationship to each other that said one profile imparts a relatively greater movement to the one lever than the spaced surfaces of the second cam profile imparts to the second lever, the intermediate surfaces of the cam profile being so shaped in relationship to each other that the intermediate surface of said second cam

profile imparts a substantial movement to the second lever while the surface of said one cam profile provides an interval of substantially no movement of said one lever.

9. Valve gear operating mechanism for steam engines, locomotives or the like in which the movements of two or more sets of valve gear are co-ordinated by means of a variable ratio transmission, said mechanism comprising a variable ratio transmission having a threaded shaft, means for rotating said shaft in clockwise and in counter-clockwise directions, single control means for controlling the rotation of said shaft, a cam nut on said shaft and actuated thereby, said cam nut having a plurality of profiles thereon, a lever connected to one set of valve gear and operable by one cam profile, and a second lever connected to another set of valve gear and operable by a second cam profile, said cam profiles being so shaped as to variably move said lever and said second lever in relationship to each other at a predetermined ratio and thereby relatively adjust the movement of said one set of valve gear and said other set of valve gear.

10. Power reverse mechanism for steam engines, locomotives or the like in which the movements of two or more sets of valve gear reversing mechanism are co-ordinated by means of a variable ratio transmission, said mechanism comprising a variable ratio transmission having a threaded shaft, means for rotating said shaft in clockwise and in counter-clockwise directions, a cam nut on said shaft and actuated thereby, said cam nut having a plurality of profiles thereon, actuating means associated with one set of valve gear and adapted to actuate said gear, said actuating means cooperating with and being operable by one cam profile, and second actuating means associated with another set of valve gear and adapted to actuate said other valve gear, the second actuating means cooperating with and being operable by a second cam profile, said cam profiles being so shaped as to variably move said actuating means and said second actuating means in relationship to one another at a predetermined ratio and thereby relatively adjust the movement of said one set of valve gear and said other set of valve gear.

11. Valve gear operating mechanism for steam engines, locomotives or the like in which the movements of two or more sets of valve gear are co-ordinated by means of a variable ratio transmission, said mechanism comprising a variable ratio transmission having a threaded shaft, means for rotating said shaft in clockwise and in counter-clockwise directions, a cam nut on said shaft and actuated thereby, said cam nut having a plurality of profiles thereon, actuating means associated with one set of valve gear and adapted to actuate said gear, said actuating means cooperating with and being operable by one cam profile, and second actuating means associated with another set of valve gear and adapted to actuate said other valve gear, the second actuating means cooperating with and being operable by a second cam profile, said cam profiles being so shaped as to variably move said actuating means and said second actuating means in relationship to one another at a predetermined ratio and thereby relatively adjust the movement of said one set of valve gear and said other set of valve gear.

12. In valve gear for steam engines, locomotives and the like having a cylinder with an admission valve, an exhaust valve and reciprocating actuation means for each valve to impart travel there-

to, valve timing means comprising a cam having at least two profiles, means for actuating said cam, admission valve setting adjusting means operatively associated with one of said cam profiles and with the admission valve actuation means, and exhaust valve setting adjusting means operatively associated with another of said cam profiles and with the exhaust valve actuation means, said cam profiles being so shaped as to variably adjust the setting of the admission and exhaust valves at a predetermined rate.

13. In valves gear for steam engines, locomotives and the like having a cylinder with an admission valve, an exhaust valve and reciprocating actuation means for each valve to impart travel thereto, valve timing means comprising a cam having at least two profiles, means for actuating said cam, admission valve setting adjusting means operatively associated with one of said cam profiles and with the admission valve actuation means, and exhaust valve setting adjusting means operatively associated with another of said cam profiles and with the exhaust valve actuation means, the cam profiles being so shaped in relationship to one another that a relatively greater adjusting movement is imparted to the admission valve than to the exhaust valve.

14. In steam engines, locomotives and the like having a cylinder with a valve for admission and cut-off and a valve for exhaust and release, a set of valve gear reversing mechanisms for the valves comprising reciprocating actuation means for each valve to impart travel thereto, valve timing means comprising a cam having at least two profiles, means for actuating said cam, admission and cut-off valve adjusting means associated with one of the cam profiles and with the admission and cut-off valve actuation means so as to impart an adjusting movement to the admission and cut-off valve to change the setting thereof, and exhaust and closure valve adjusting means associated with another cam profile and with the exhaust and release valve actuation means so as to impart an adjusting movement to the exhaust and closure valve to change the setting thereof, the cam profiles being so shaped in relationship to each other that a relatively greater adjusting movement is imparted to the admission and cut-off valve than to the exhaust and closure valve.

15. In steam engines, locomotives and the like having a cylinder with a valve for admission and cut-off and a valve for exhaust and release, a set of valve gear reversing mechanisms for the valves comprising reciprocating actuation means for each valve to impart travel thereto, valve timing means comprising a cam having at least two profiles, means for actuating said cam, admission and cut-off valve adjusting means associated with one of the cam profiles and with the admission and cut-off valve actuation means so as to impart an adjusting movement to the admission and cut-off valve to change the setting thereof, and exhaust and closure valve adjusting means associated with another cam profile and with the exhaust and release valve actuation means so as to impart an adjusting movement to the exhaust and closure valve to change the setting thereof, said one cam profile having two surfaces for imparting an adjusting movement to the admission and cut-off valve adjusting means to thereby adjust the setting of the admission and cut-off valve, said surfaces being spaced from one another in the direction of travel of the cam and

15

connected by an intermediate surface, one of the spaced surfaces adjusting the setting of the admission and cut-off valve to govern the forward movement of the steam engine, locomotive or the like and the other of said spaced surfaces adjusting the setting of said valve to govern the reverse movement of said steam engine, the intermediate surface providing an interval in which substantially no adjustment is made to the setting of the admission and cut-off valve, said other cam profile being shaped to impart a relatively lesser adjusting movement to the exhaust and closure valve adjusting means than is imparted to the admission and cut-off valve adjusting means during said forward and reverse movements and to impart a substantial adjusting movement to the exhaust and closure valve adjusting means during said interval between said portions.
